METHOD OF CONVERTING SOLID CARBON DIOXIDE TO GASEOUS FORM AND APPARATUS THEREFOR

Roy E. McIlrath, Wilmette, Ill.

Application July 3, 1936, Serial No. 88,778

6 Claims. (CL 62—115)

The invention relates to an improved method of converting carbon dioxide from solid to gaseous form and to an improved apparatus especially adapted to carry out the method.

- 5 The primary object of the invention is to provide an improved method of converting carbon dioxide from solid to gaseous form, of such character that the change takes place almost instantaneously after the process is initiated, thus particularly adapting the same for use in replenishing the supply of gaseous carbon dioxide in a refrigerating system, for example, where the replenishing operation must be consummated with great rapidity.
- 10 15 A more specific object of the invention is to provide an improved method of changing solid carbon dioxide to gaseous form in which a portion of hot compressed gaseous carbon dioxide is circulated in heat exchange relation with a confined quantity of solid carbon dioxide to convert the latter into gaseous form at a relatively high pressure.

Another object of the invention is to provide a novel apparatus for circulating hot gaseous carbon dioxide in heat exchange relation with a portion of solid carbon dioxide to convert the latter quickly and efficiently into gaseous carbon dioxide.

A further object of the invention is to provide 30 a refrigerating apparatus in which gaseous carbon dioxide is successively compressed, condensed and evaporated and including an improved arrangement for replenishing the charge of gaseous carbon dioxide at will from a source of solid carbon dioxide.

Further objects and advantages of the invention will become apparent as the following description proceeds and the features of novelty which characterize the invention are pointed out 40 with particularity in the claims annexed to and forming a part of this specification.

For a better understanding of the invention, reference may be had to the accompanying drawing in which the single figure is a diagrammatic 45 representation of a refrigerating apparatus embodying the present invention.

Referring more particularly to the drawing, a preferred apparatus has been illustrated for carrying out the improved method of converting solid 50 carbon dioxide to gaseous carbon dioxide contemplated by the present invention. In general, this method includes as its primary step the circulation of hot gaseous carbon dioxide in heat exchange relation with a portion of solid carbon dioxide in order to convert the latter into gaseous

form. When the solid carbon dioxide is used as a source for replenishing the supply or charge of gaseous carbon dioxide in a compressor-condenser-evaporator refrigerating system a portion of the hot gaseous refrigerant discharged by the compressor may conveniently be directed in heat exchange relation with the solid carbon dioxide and such an arrangement is illustrated in the drawing.

The particular apparatus shown embodies a 10 refrigerating machine including as its principal elements compressor 10, a condenser 11, and an evaporator 12, all connected in orbital relation. Gaseous refrigerant such as carbon dioxide is compressed by the reciprocating type compressor 10, which includes a cylinder 13 and reciprocable piston 13^a driven by a suitable prime mover (not shown). The compound gaseous refrigerant is discharged therefrom through a suitable exhaust valve 14^a into an outlet conduit 14. The gaseous refrigerant passes through the conduit 14 and a conduit 15 to the condenser 11. In the case of a carbon dioxide refrigerating machine the gaseous refrigerant is ordinarily discharged from the compressor at a pressure of approximately 1000 15 pounds per square inch and a temperature of from 200° to 240° F. The hot compressed gaseous refrigerant flowing through the condenser 11 is condensed by the transfer of heat therefrom to 20 a cooling medium in the condenser. The particular condenser shown is of the water cooled type, water being circulated through a casing 16 from an inlet 16^a to an outlet 16^b over the surfaces of a helical refrigerant coil 17 and in heat exchange relation therewith, the refrigerant 25 being liquefied by the transfer of heat to the cooling water. The refrigerant thus liquefied in the condenser 11 is supplied through a conduit 18 and expansion valve 19 to the dry type evaporator 12 in which it is evaporated by the absorption of 30 heat from the surrounding medium to be cooled. The evaporated refrigerant is then returned from the evaporator 12 to the compressor 10 through an exhaust conduit 20 communicating with the interior of the cylinder 13 through a suitable 35 inlet valve 20^a. This cycle is repeated and continued until the temperature of the zone in which the evaporator 12 is located is reduced to a desired value.

Refrigerating machines of the type described 40 are frequently used in air-conditioning installations for large public buildings as well as in refrigerating plants of various sorts, because of the non-toxic character of the refrigerant. In all such installations varying amounts of leakage of 45

the gaseous refrigerant will be had. This leakage ordinarily occurs in relatively small quantities at the compressor piston valves and various pipes or conduit joints. In addition, there is greater likelihood of leakage of a large amount of the charge of refrigerant due to a rupture of some part of the apparatus in view of the extremely high pressures encountered. It has heretofore been proposed to provide a reserve supply of carbon dioxide in liquid form contained in a high pressure tank. Such an arrangement is disadvantageous, however, in that carbon dioxide in this form is relatively expensive. Difficulty has also been encountered in attempting to use solid carbon dioxide as a reserve source of refrigerant since even though the material may be had much more cheaply in this form, no method nor apparatus has heretofore been available for quickly converting solid carbon dioxide into gaseous form. Thus, if a quantity of say 75 pounds of solid carbon dioxide is confined in a metal tank at ordinary room temperature, it will require approximately twelve hours for it to sublime or change into gaseous form. Although such a slow conversion rate might be adequate for supplying small replenishments to a refrigerating system, it would be altogether unsuited to take care of an emergency condition in which a large portion of the original charge of gaseous carbon dioxide in the refrigerating machine had been lost. The present invention contemplates a method and apparatus for converting solid carbon dioxide from solid to gaseous form almost instantaneously so that it will be readily available whatever the character of the condition requiring its use.

In the apparatus shown in the drawing, a reserve supply of carbon dioxide in the form of solid blocks 21 is contained in a hermetically sealed cylindrical metal tank or container 22. This tank may conveniently be supported adjacent the refrigerating machine which it is adapted to supply. A portion of the hot gaseous refrigerant discharged from the compressor 10 is circulated in heat exchange relation with the blocks of solid carbon dioxide 21 within the container 22. Thus, a by-pass conduit 24 directs a portion of the compressed gaseous carbon dioxide from the conduit 14 to the interior of the container 22. A manually operable valve 25 is provided at the juncture of the conduits 24 and 14 in order to control the flow of gaseous refrigerant through the conduit 24. This valve simply opens and closes the inlet of the conduit 24 and does not obstruct the flow of fluid through the conduit 14. The solid carbon dioxide is ordinarily at a temperature of approximately 77° below zero F. while the compressed gaseous carbon dioxide supplied through the conduit 24 enters the container at a temperature of approximately 200° F. This hot gaseous carbon dioxide circulating in contact with the solid carbon dioxide quickly converts it into gaseous form. This action is enhanced by the speed of flow of the compressed gas entering the container at a pressure of approximately 1000 pounds per square inch since the gas sublimed from the blocks of solid carbon dioxide is quickly carried away from the surface so that it cannot form a heat insulating layer of cool gas about the same having a relatively low heat conductivity.

Upon conversion of the solid carbon dioxide in the container 22 to gaseous form, the pressure in the container attains a value of approximately 900 pounds per square inch, the volume of the

container being of the same order of magnitude as that of the original filling of solid carbon dioxide. The gaseous carbon dioxide thus formed as well as the gas supplied to the container 22 from the compressor is returned to the refrigerating system through a conduit 26. This conduit 26 communicates with the intake conduit 20 of the compressor 10 through a manually operable valve 27. This valve controls only the flow of fluid in the conduit 26 and not the flow in conduit 20. A manually operable valve 28 may also conveniently be located at the outlet of the container 22. In some cases, the solid carbon dioxide within the container 22 may be converted to liquid rather than to gaseous form. The pressure at the intake of the compressor 10 is ordinarily of the order of about 400 pounds per square inch as compared to the pressure of 900 pounds per square inch in the container 22, however, so that any liquid carbon dioxide flowing through the conduit 26 expands rapidly as it passes through the valve 27 into the conduit 20 and thus is converted into gaseous form. The flow of gas through the conduit 20 during the normal operation of the refrigerating machine carries away any frost formed at the valve 27 during this expansion and thus prevents clogging of the same.

It will thus be seen that a by-pass is provided between the high and low pressure sides of the refrigerating machine or system, these high and low pressure sides being separated by the expansion valve 19. In the apparatus shown the by-pass is formed by conduit 24, container 22 and conduit 26, and serves to direct hot gaseous carbon dioxide in heat exchange relation with the solid carbon dioxide.

In the operation of the apparatus described above, the operator of the refrigerating machine is apprised of any loss of carbon dioxide in the machine by the usual gauges or other measuring devices. In case there is such a loss and the necessity for replenishment of the charge thus arises, the valve 25 is first opened. Upon such opening of the valve 25, gaseous carbon dioxide is supplied to the interior of the container 22 through the conduit 24 at a relatively high pressure and temperature. The solid carbon dioxide within the container 22 is then rapidly converted into gaseous form as described above. After such conversion the valve 27 is opened, thus admitting the desired quantity of gaseous carbon dioxide to replenish the charge in the machine. The conversion of carbon dioxide from solid to gaseous form takes place so rapidly in the improved apparatus that the valve 27 may be opened as soon as the operator has completed opening of the valve 25. After all of the solid carbon dioxide within the container 22 has been converted into gaseous form, the valves 25 and 27 may be closed and the container 22 refilled through a suitable aperture in the top of the container which is normally closed by a gas tight cover plate 28.

Although a particular application and embodiment of the invention have been shown and described in some detail for the purposes of illustration, the invention is not limited to such particular application and embodiment but on the other hand, the appended claims are intended to cover all modifications within the spirit and scope of the invention.

I claim as my invention:

1. The method of replenishing a charge of gaseous carbon dioxide in a compression-condensing-expansion cycle refrigerating machine, which comprises, sequentially compressing, con-

densing and expanding a charge of carbon dioxide in a refrigerating cycle, circulating a portion of the hot compressed gaseous carbon dioxide in direct surface contact with a portion of solid carbon dioxide after the compression stage and prior to the condensation stage, maintaining the gaseous and solid carbon dioxide continuously under pressure, and returning the resulting gaseous carbon dioxide as well as such portion of the compressed gaseous carbon dioxide to the original charge.

2. The method of replenishing a charge of gaseous carbon dioxide in a compression-condensing-expansion cycle refrigerating machine, which comprises, sequentially compressing, condensing and expanding a charge of carbon dioxide in a refrigerating cycle, circulating a portion of the hot compressed gaseous carbon dioxide in heat exchange relation with a portion of solid carbon dioxide after the compression stage and prior to the condensation stage, and introducing the resulting gaseous carbon dioxide as well as such portion of the compressed carbon dioxide into the expanded carbon dioxide in the machine.

3. The method of operating a refrigerating machine, which comprises, sequentially compressing, condensing and expanding a charge of gaseous carbon dioxide and replenishing such charge of gaseous carbon dioxide by circulating a portion of the compressed and uncondensed charge in heat exchange relation with a body of solid carbon dioxide and introducing the resulting gaseous carbon dioxide into the original charge.

4. The method of operating a compression

type refrigerating machine having high and low pressure sides containing a charge of carbon dioxide which comprises by-passing a portion of the carbon dioxide from the high pressure to the low pressure side of the machine, circulating the carbon dioxide in heat exchange relation with a portion of solid carbon dioxide, and introducing the gaseous carbon dioxide derived from the solid carbon dioxide into the low pressure side of the machine.

5. The combination of a refrigerating system having high and low pressure sides and adapted to contain a charge of carbon dioxide, means for by-passing a portion of the charge from said high pressure side to said low pressure side, means for confining a quantity of solid carbon dioxide in heat exchange relation with the portion of the charge flowing through said by-pass means, and means for introducing gaseous carbon dioxide derived from the solid carbon dioxide into said low pressure side of said system.

6. A refrigerating apparatus comprising, in combination, a compressor, a condenser, and an evaporator connected in orbital relation and adapted to contain a charge of gaseous carbon dioxide, means including a hermetically sealed container for confining a portion of solid carbon dioxide as a reserve supply for the charge in the apparatus, means operable at will for by-passing a portion of the compressed gaseous carbon dioxide discharged from said compressor through said container to convert the solid carbon dioxide contained therein into gaseous form, and means for conveying a regulated quantity of the converted carbon dioxide to said compressor.

ROY E. McILRATH.
